ABSTRACT: A volume controller for controlling the voltage of at least one signal transmitted in a signal path in matching with the characteristic impedance of the signal path, where the signal is branched to two differential outputs by a branch circuit comprising a bridge circuit of four resistance-arms to amplify the difference between the two differential outputs in a difference amplifier which has a feedback circuit comprising a variable resistor connected between the output of the difference amplifier and one of two inputs of the difference amplifier. The voltage of the output of the difference amplifier can be controlled within an extremely wide level range in response to control of the control means which gangs the variable resistor of the feedback circuit and variable one of the four resistor-arms of the bridge circuit.

VOLUME CONTROLLER

This invention relates to volume controllers for controlling the voltage of signal transmitted in a signal-path, such as audio line, and more particularly to a volume control unit suitable to an element of a fader.

There have been proposed many kinds of volume controllers of this type. However, conventional volume controllers have disadvantages, such as narrow control range, fluctuation of distortion factor of the controlled signal in response to the change of signal-level, and mismatching with the characteristic impedance of the transmission line. Moreover, the conventional volume controller is usually unsuitable to be remote-controlled by an external signal or signals.

An object of this invention is to provide volume controllers eliminatable of the above mentioned disadvantages and having an extremely wide control range.

Another object of this invention is to provide a volume control unit of a fader suitable to be remote-controlled by an external control voltage.

The principle of this invention will be better understood from the following more detailed discussion taken in conjunction with the accompanying drawings, in which the same or equivalent parts are designated by the same reference numerals, characters and symbols, and in which:

FIG. 1 is a block diagram for describing the principle of this invention;

FIG. 2 is a circuit diagram for illustrating an embodiment of this invention;

FIG. 3 illustrates a characteristic curve for describing the operation characteristic of the embodiment shown in FIG. 2;

FIG. 4 is a circuit diagram for illustrating another embodiment of this invention;

FIGS. 5A and 5B illustrate characteristic curves for describing the operation characteristic of the embodiment shown in FIG. 4; and

FIG. 6 is a circuit diagram for illustrating another embodiment of this invention.

With reference to FIG. 1, the principle of this invention will first be described. A matching circuit 2 matches with the line impedance within the range of all operation frequencies. An input signal S_i applied from an input terminal 1 passes through the matching circuit 2 and is applied to a branch circuit 3, which produces two branched outputs S_1 and S_2 . These two outputs S_1 and S_2 are respectively applied to two inputs of a difference amplifier 4. The output of this difference amplifier 4 is fed back to one of the two inputs of the difference amplifier 4 through a feedback circuit 5. An output signal S_o is derived from an output terminal 6 connected to the output of the difference amplifier 4. Details of the construction and operation of this volume controller will be understood from the following description of embodiments of this invention.

FIG. 2 shows an embodiment of the volume controller of this invention having the above-mentioned construction. In FIG. 2, a resistor R_1 is a matching resistor, and a resistor R_2 is a coupling resistor. The branch circuit 3 is composed of a bridge circuit having four resistor-arms (resistors R_3 , R_4 and R_6 and a variable resistor R_5) and if two pair of opposed terminals (P_1 , P_2) AND (P_3 , P_4). The signal S_i is applied, through the resistor R_2 , to one pair of opposed terminals P_1 and P_2 , and two outputs S_1 and S_2 branched at the other of opposed terminals (P_3 , P_4) are respectively applied to a minus input terminal I_1 of the difference amplifier 4 and a plus input terminal I_2 thereof. A resistor 8 is a matching resistor of output side. A variable resistor R_7 is a feedback resistor and gangs with the variable resistor R_5 .

In the above-mentioned construction, if the difference amplifier 4 has a gain G with respect to the input signal S_i of the minus terminal I_1 , the input impedance Z_i of the difference amplifier 4 at the minus terminal I_1 can be indicated as follows:

$$Z_i = \frac{r_7}{1+G} = \frac{r_7}{1+(r_7/r_6)} = \frac{1}{(1/r_6)+(1/r_7)} \quad (1)$$

where reference r_6 and r_7 are respectively resistances of the resistors R_6 and R_7 .

Therefore, the equilibrium condition of the bridge circuit 3 can be indicated as follows:

$$\frac{r_3}{r_4} = \frac{r_5}{r_6//Z_i} = \frac{r_5}{1/(r_6/2)+1/r_7} \quad (2)$$

where references r_3 and r_4 are respectively resistances of the resistors R_3 and R_4 while the term $r_6//Z_i$ indicates a resultant resistance of parallel-connected resistors r_6 and Z_i .

If each of the resistors R_5 and R_7 is a variable resistor of resistance 500 kilo-ohms, and the bridge circuit 3 balances when the variable resistor R_7 has the value of 500 ohms, then the equation (2) is as follows, where resistances r_3 and r_6 have the respective values of 40 kilo-ohms and 3 kilo-ohms:

$$\frac{40000}{r_4} = \frac{500}{1} = \frac{500}{3.75} = 1.365 \quad (3)$$

Therefore, the resistance r_4 of the resistor R_4 becomes a value 29.4 kilo-ohms.

Moreover, the equilibrium condition of the bridge circuit 3 can be indicated as follows by use of the resistances r_3 , r_4 , r_5 , r_6 and r_7 from the equation (2):

$$r_5 = \frac{r_3}{r_4} \left(\frac{1}{\left(\frac{1}{r_6/2} + (1/r_7) \right)} \right) \quad (4)$$

If respective input voltages of the minus and plus terminals I_1 and I_2 of the difference amplifier 4 are assumed as voltages E_{11} and E_{12} respectively, since influences from relatively high resistances R_2 , R_3 and R_4 are negligible, the output voltage E_o of the difference amplifier 4 can be indicated as follows:

$$E_o = \frac{r_6 + r_7}{r_6} \frac{dE_i}{i_2 - i_1} \quad (5)$$

Where "dE_i" indicates a difference between the voltages E_{11} and E_{12} . In this case, since the resistance r_6 of the resistor R_6 is constant, the output voltage E_o can be indicated by a function of the resistance r_7 of the resistor R_7 and the input voltages E_{11} and E_{12} . Moreover, if the bridge circuit 3 is balanced so that the voltages E_{11} and E_{12} are equal to each other, the output voltage E_o becomes zero and the attenuation in the volume controller of this invention becomes maximum. The output voltage E_o is adjustable to a desired value in accordance with change of the resistance r_7 of the resistor R_7 and of the voltages E_{11} and E_{12} .

FIG. 3 shows an attenuation characteristic of the embodiment shown in FIG. 2 in case where the variable resistors R_5 and R_7 have the same change-characteristic of resistance and the maximum resistance 500 kilo-ohms. The maximum attenuation A_{max} of this characteristic exceeds 120 db. (decibels). Accordingly, it is understood that the attenuation ratio of the output voltage E_o to the input signal S_i applied from the input terminal 1 can be changed within an extremely wide changing range in accordance with change of the resistance of a gang resistor comprising the variable resistors R_5 and R_7 .

FIG. 4 shows another embodiment of this invention in which attenuation ratio of an output voltage E_o to a voltage of input signal S_i can be changed by an external control voltage V_c applied across a pair of control terminals 10a and 10b. In this embodiment, the variable resistor R_5 is composed of a photoconductive cell whose resistance varies with the illumination on the cell, and the resistor R_7 is composed of a resistor R_{7b} and a photoconductive cell R_{7a} which are connected in parallel with each other. Such photoconductive cell can be formed by use of cadmium sulfide (CdS) wafer. The photoconductive cells R_5 and R_{7a} are respectively illuminated by small electric lamps L_2 and L_1 which are excited by an external control voltage V_c supplied, as a manipulated variable,

across the terminals 10a and 10b. The photoconductive cell R_{1a} and the small electric lamp L₁ forms a voltage-photoreistance transducer PD₁, and the photoconductive cell R_{2a} and the small electric lamp L₂ forms similarly a voltage-photoreistance transducer PD₂. Accordingly, the resistances of the photoconductive cells R_{1a} and R_{2a} are commonly controlled by the external control voltage V_c. A variable resistance R₉ is employed for compensating discordance between characteristics of the transducers PD₁ and PD₂. Other parts are the same as those of the embodiment shown in FIG. 2.

In each of the photoconductive cells R_{1a} and R_{2a} is formed by use of CdS wafer, a characteristic curve shown in FIG. 5B is obtained as the characteristic of the transducers PD₁ and PD₂. In this case, the attenuation ratio of the output voltage E_o to the voltage of the input signal S_i can be changed as shown in FIG. 5A in response to change of the voltage across the electric lamps L₁ and L₂. In this characteristic, the maximum attenuation ratio A_{max} is obtained at six volts of the control voltage V_c.

FIG. 6 shows another embodiment of this invention in which the output voltage E_o can be controlled by an external control voltage V_c and moreover the controlled output voltage E_o can be automatically regulated to a substantially constant level. In this embodiment, the output voltage E_o is rectified by a rectifier (e.g.; full-wave rectifier 12) after amplification by an amplifier 11. The rectified output of the full-wave rectifier 12 is superposed on the external control voltage V_c so as to coincide with the polarity of the external control voltage V_c. Accordingly, this embodiment has an automatic gain control loop. If the output voltage E_o increases, the attenuation ratio increases also. Therefore, the controlled output voltage E_o of the embodiment shown in FIG. 6 can be regulated at a constant level. The time constant of the automatic gain control loop can be determined at a desired value by inserting, at the output side of the full-wave rectifier 12, a smoother having a time constant which corresponds to the desired value.

As mentioned above, the volume controller of this invention can control an input signal or signal within a wide level range. Moreover, the embodiment shown in FIGS. 4 and 6 can perform automatically such control. Therefore, the volume con-

troller of this invention is suitable for use as an element of a fader which is employed to control the level of each of two separated but related audiosignals or to control simultaneously the levels of combined audiosignals in an audio system, such as broadcast system.

What we claim is:

1. A volume controller for controlling the voltage of at least one signal transmitted in a signal path, comprising:

a bridge circuit including four resistor arms and having a pair of opposed input terminals and a pair of opposed output terminals, wherein one of said resistor arms comprises a first variable resistor;

a matching circuit connected between said bridge circuit input terminals and the output of a signal path;

a difference amplifier having an output terminal, and having a pair of input terminals connected to the output terminals of said bridge circuit for amplifying the difference between signals at said bridge circuit output terminals;

a feedback circuit comprising a second variable resistor connected between the amplifier output terminal and one of the amplifier input terminals;

and control means for simultaneously varying said first and second variable resistors; wherein the voltage at the amplifier output can be attenuated over a wide range in response to operation of said control means to vary said first and second variable resistors.

2. A volume controller according to claim 1, in which said

first and second variable resistors are photoconductive cells; and in which the control means comprises two small electric lamps for illuminating the respective photoconductive cells, and a variable voltage source connected to said lamps for varying the illumination thereof.

3. A volume controller according to claim 2, further comprising a rectifier connected to said amplifier output terminal and means connected between said rectifier and said variable voltage source for superposing a rectified amplifier output signal on the voltage of said variable voltage source, whereby the controlled output of the difference amplifier is maintained at a substantially constant level.
